UNITED STATES PATENT OFFICE

170,192

AIRCRAFT SKI OR SIMILAR ARTICLE

Howard S. Green, Wilmington, Del., assignor, by
mesne assignments, to All American Engineering
Company, Wilmington, Del., a corporation
of Delaware

Application November 5, 1952, Serial No. 22,135

Term of patent 14 years

(Cl. D34—14)

To all whom it may concern:

Be it known that I, Howard S. Green, a citizen of the United States and a resident of the city of Wilmington, county of New Castle, State of Delaware, have invented a new, original, and ornamental Design for an Aircraft Ski or Similar Article, of which the following is a specification, reference being had to the accompanying drawing, forming part thereof, in which:

Figure 1 is a plan view of an aircraft ski or similar article, showing my new design;

Figure 2 is a side elevation of the same; and

Figure 3 is a cross sectional view on the section line 3—3 in Figure 1.

I claim:

The ornamental design for an aircraft ski or similar article, substantially as shown.

HOWARD S. GREEN.
